US0D1066684S

(12) United States Design Patent (10) Patent No.: US D1,066,684 S
(45) Date of Patent: * Mar. 11, 2025

(54) APPLICATOR

(71) Applicant: Droplette Inc., Boston, MA (US)

(72) Inventors: Madhavi Gavini, Cambridge, MA (US); Rathi Srinivas, Boston, MA (US); Joshua Harris, Swampscott, MA (US); Peter Stokes, Boston, MA (US); Rebecca Conway, Boston, MA (US)

(73) Assignee: DROPLETTE INC., Boston, MA (US)

() Term: 15 Years

(21) Appl. No.: 29/810,062

(22) Filed: Sep. 30, 2021

(51) LOC (15) Cl. 24-01

(52) U.S. Cl.

USPC D24/214; D24/188

(58) Field of Classification Search

USPC D24/146, 200, 203, 205, 206, 207, 214;

D28/7, 9, 99

CPC A61H 2205/022; A61H 2201/10; A61H 2201/0153; A61H 7/005; A61H 9/0057;

(57) CLAIM

The ornamental design for an applicator, as shown and described.

DESCRIPTION

FIG. 1 is a perspective view of an applicator, showing our new design;

FIG. 2 is a side view thereof;

FIG. 3 is another side view thereof;

FIG. 4 is a top view thereof;

FIG. 5 is a bottom view thereof;

FIG. 6 is a front view thereof;

FIG. 7 is a rear view thereof; and,

FIG. 8 is a lower perspective view thereof.

The broken lines in the drawings depict portions of the applicator that form no part of the claimed design.

1 Claim, 8 Drawing Sheets
